E. H. ARBUCKLE.

ADJUSTABLE SINK.

APPLICATION FILED JULY 20, 1921.

1,391,091.

Patented Sept. 20, 1921.

UNITED STATES PATENT OFFICE.

EMERY H. ARBUCKLE, OF CLEVELAND, OHIO.

ADJUSTABLE SINK.

1,391,091.

Specification of Letters Patent. Patented Sept. 20, 1921.

Application filed July 20, 1921. Serial No. 486,070.

To all whom it may concern:

Be it known that I, EMERY H. ARBUCKLE, a citizen of the United States, residing at Cleveland, in the county of Cuyahoga and State of Ohio, have invented certain new and useful Improvements in Adjustable Sinks, of which the following is a specification.

This invention relates to adjustable kitchen sinks and more particularly to an improved apparatus for adjustably supporting a sink and drain board in a manner that will permit the sink and drain board to be raised or lowered as desired.

One of the objects of the invention is to provide adjustable brackets for the sink and drain board which may be easily adjusted to place the sink and drain board at the desired height and which will include an arrangement whereby the spigot may be maintained in the desired position with respect to the sink.

Other objects of the invention will appear upon consideration of the following detail description and accompanying drawings, wherein:—

Figure 1 is a perspective view of the apparatus constructed in accordance with my invention showing the conventional form 30 of sink in dotted lines mounted upon the apparatus.

Fig. 2 is a vertical section through the same.

Fig. 3 is a detail section through the connection between the drain board and sink.

Referring to the drawing by numerals, the main bracket structure 1 supports the sink 2 and this bracket includes the supporting plate 3 which extends longitudinally 40 with respect to the bottom of the sink and has a transverse supporting arm 4 integrally formed with a vertical standard 5 the latter being provided with laterally projecting lugs 6 arranged in vertical spaced relation. The lowermost lug 6 is provided with an opening through which the adjusting standard projects and the wall back of the sink is provided with a supporting lug or bearing 8 to receive the lower end of the member 7. A square portion 9 is provided for conveniently receiving a wrench whereby the standard 7 may be turned. The upper end of the standard 7 above the upper lug is mounted in another lug 10 as shown 55 in Fig. 2 and the standard 7 is provided with screw threads 11 throughout a portion

of its length the uppermost lug 6 on the bracket being screw threaded to engage the screw threads on the standard as shown. The sink 2 is attached to the cross arm 4 by 60 the lugs 12 and it will be obvious from this construction that when the standard or screw threaded rod 7 is turned, the bracket will be raised or lowered to raise or lower the sink. 65

The back panel 13 of the sink is provided with suitable openings to receive the spigot 14 and a special fitting 15 is provided to be connected to the water supply pipe 16. This fitting 15 includes a plurality of removable plugs 17 mounted in openings in the fitting which receives the supply of water from the pipe 16 so that when the spigot 14 is removed and the sink adjusted, the spigot 14 may be placed in any one of 75 the openings from which a removable plug 17 has been removed.

Provision for making the adjustment in the drain pipe is shown in Fig. 1 and the upper end of the drain pipe 18 is fitted with 80 a telescoping pipe 19 which connects to the drain opening 20 in the sink, thus accommodating the sink to the drain pipe in a manner that will permit the adjustment as above stated. 85

An auxiliary supporting bracket 21 is provided for one or both ends of the sink in the event the sink is larger than could ordinarily be supported by the main bracket. This auxiliary bracket includes the cross arm 22 carried by the standard 23 which is provided with lugs 23' attached to a vertical rod 24 whereby the lugs may be longitudinally mounted on the rod 24 and secured in position by set screws. 95

The drain board 25 is supported by the drain board bracket 26 which includes the cross arm 27 and the supporting plate 28 mounted on a standard which is provided with a bracket 29 having a vertical rod 30 connected thereto, the latter being mounted in a bearing 31 whereby the vertical adjustment will be permitted.

In this manner it will be seen that the entire sink and drain board may be vertically 105 adjusted to the desired height by simply placing a wrench on the square portion 9 and turning the standard 7.

Connection between the drain board 25 and the edge of the sink is made by a fastening plate 32 provided with screws 33 which engage the marginal edges of the sink 110

as shown in Fig. 3 to maintain these two elements in proper relation and against accidental displacement.

Minor changes may be made in the details 5 of construction and accompanying drawings without departing from the spirit of the invention or the scope of the claims hereunto appended.

What is claimed is:—

- 10 1. The combination with a sink, a bracket including a longitudinal plate and a transverse cross arm engaged with the bottom of the sink, a standard supporting the plate and cross arm, and provided with laterally projecting lugs, the uppermost lug being screw threaded, an adjusting rod provided with screw threads received in the screw threads in the said lug, the lower end of the said adjusting rod being provided with a support, and a square portion of the rod adapted to be engaged with a wrench whereby the said adjusting rod may be manually turned.
- 15 2. The combination with a sink, a bracket including a supporting plate and cross arm, a standard supporting the said plate and cross arm, and equipped with laterally projecting lugs, a vertically disposed adjusting rod engaged with the said lug, the said rod having screw threads to mesh with the screw threads in the lugs whereby the bracket may be vertically adjusted when the lug is turned, the upper portion of the sink being equipped with a spigot, a fitting connected 30 with the source of water supply and having a plurality of openings equipped with plugs, the said plugs being adapted to be removed whereby the spigot may be located in a position in the fitting with respect to the adjusted position of the said sink.
- 35 40 3. In combination with a sink and drain

board, a bracket supporting the sink, a second bracket to support the drain board, each of the said brackets being provided with lugs arranged in pairs and having vertically 45 alined openings, an adjusting rod mounted in the openings in the said sink bracket, the said rod having screw threads engaging screw threads on one of the lugs on the sink bracket, means to turn the said adjusting 50 rod, a supporting rod for the said drain board bracket, slidably mounted in the openings in the said lugs, and means to adjustably connect the sink to a drain pipe.

4. In combination with a sink, and drain 55 board, a bracket supporting the sink, a second bracket to support the drain board, each of the said brackets being provided with lugs arranged in pairs and having vertically 60 alined openings, an adjusting rod mounted in the openings in the said sink bracket, the said rod having screw threads engaging screw threads in one of the lugs on the sink bracket, means to turn the said adjusting 65 rod, a supporting rod for the said drain board bracket, slidably mounted in the openings in the said lugs, and means to adjustably connect the sink to a drain pipe, the 70 said sink having a water supply pipe, a spigot and a fitting attached to the water supply pipe and provided with a plurality of openings, each opening being equipped with a removable plug whereby the said spigot may be disposed in any one of the 75 said openings in the fitting.

In testimony whereof, I have affixed my signature in the presence of two witnesses.

EMERY H. ARBUCKLE.
